UNITED STATES PATENT OFFICE.

JOSEPH W. FISKE, OF NEW YORK, N. Y.

DESIGN FOR SETTEE.

Specification forming part of Design No. 5,147, dated August 1, 1871.

To all whom it may concern:

Be it known that I, JOSEPH W. FISKE, of New York, in the county and State of New York, have invented and produced a new and original Design for Settees, of which the following is a specification:

The nature of my design is fully represented in the accompanying drawing, to which reference is made.

I claim as my invention—

The design for a settee, as shown.

Witnesses: J. W. FISKE.

B. UNDERWOOD,
FORMAN WHITNEY.
